ADOLF BARGEBOER, OF ROTTERDAM, NETHERLANDS.

MACHINE FOR MAKING CIGARILLOS AND THE LIKE.

Application filed November 5, 1921. Serial No. 513,173.

To all whom it may concern:

Be it known that I, ADOLF BARGEBOER, a subject of the Queen of the Netherlands, residing at Rotterdam, Netherlands, have 5 invented certain new and useful Improvements in Machines for Making Cigarillos and the like, of which the following is a specification.

In the manufacture of cigarillos machines 10 are employed comprising a hollow casting having a curved top face forming a rolling table provided with a groove or depression for receiving the tobacco and adjacent to said groove with a number of perforations. 15 A belt of leather or other suitable material stretched over said curved top face is passed over a set of two rollers arranged the one over the other and adapted to reciprocate along the table, the belt being likewise 20 provided with perforations to coact with those in the table.

The wrapper, i. e. the tobacco-leaf in which the roll of tobacco is to be wrapped, is placed on the perforated portion of the 25 leather belt and caused to be held thereon by atmospheric pressure owing to a vacuum being set up in the hollow casting. After the tobacco has been deposited on the leather belt vertically above the groove in the rolling 30 table and forced thereinto together with that portion of the belt by which it is supported, the rollers over which the belt is passed are moved along the table whereby the tobacco is lifted out of the groove and 35 rolled in the wrapper, which has one of its edges gummed, whereupon the complete cigarillo is discharged.

It has already been suggested to employ 40 in combination with a machine of the above type a second hollow member or receiver, and a third hollow member or transporter, these members having a perforated cover and a perforated bottom respectively and each provided with means for producing a 45 vacuum therein, the transporter being adapted for movement between and for alternate cooperation with the rolling table and the receiver. In such machines the wrapper is placed on the perforated cover of 50 the receiver and subsequently conveyed by the transporter to the rolling table, it being understood that vacuum is successively set up in the receiver, in the transporter and in the hollow casting forming the rolling 55 table.

My present invention has for its object

certain improvements of the last mentioned type of machines and more particularly to provide improved means whereby the wrapper while supported by the receiver may be automatically gummed and cut so that from the moment an attendant has placed a wrapper on the receiver no further manual operations are required and the manufacture of the cigarillo is performed throughout 60 automatically.

With this object in view I provide a frame carrying the transporter, a cutting roller and a gumming brush, and I support this frame at one side by an arm coacting with the usual cams for actuating the perforated belt, at the other side by a suitably driven second arm. I further allow this frame to coact with the stationary receiver which I provide with a knife having its cutting edge 70 turned upwards, the arrangement being so that when the frame moves towards the receiver the cutting roller attached thereto moves over the knife edge, and that subsequently the transporter is placed in proper 75 position on the receiver.

As to the gumming of the wrapper, this ordinarily offers serious difficulties owing, amongst others, to the irregular form of the wrapper and to the requirement that the gumming brush should be prevented from contact with the knife. I therefore provide the perforated cover of the receiver with an outwardly sloping end portion the extreme edge of which is normally at a certain distance above the knife edge. I further hinge 80 said cover along the side opposite the sloping portion and I provide means whereby it is yieldingly held in its normal position, the arrangement being such that when the 85 gumming brush moves in contact with said sloping portion the cover will not yield and the knife edge cannot be gummed, but that during the movement of the cutting roller over the receiver the cover is depressed so 90 as to uncover the knife.

The presence of holes in the wrapper may cause some glue to adhere to the outwardly sloping end portion of the receiver cover. In order now to prevent the cutting roller 100 from taking up this glue I provide the frame carrying this roller with an abutment adapted for coaction with a projection of the hinged receiver cover so that the cover is sufficiently depressed when the cutting 105 roller moves over same.

Another inconvenience experienced in

prior constructions is that during the transport of the wrapper the gummed edge of the same may curl whereby the wrapper would not assume the proper position on the roller table. In order to overcome this difficulty I propose to provide the transporter with a movable member having a flat face adapted during the transport of the wrapper from the receiver to the rolling table to contact with the gummed edge through its entire length so that said edge sticks to this face. The said member, which may be termed edge protector, is adapted to be forced out of contact with the gummed edge of the wrapper after the latter has been deposited on the rolling table and held thereon by atmospheric pressure so that the gummed edge is prevented from curling. The movement of the edge protector off the wrapper may simply be brought about by a push arm secured to the stamper for forcing the tobacco into the rolling table groove, and a stationary abutment may be provided on the receiver for returning the edge protector into its original position.

The annexed drawing illustrates, by way of example only, an embodiment of my present invention, Figure 1 being a side elevational view thereof showing some parts in cross section, whereas Figs. 2 and 3 are a side elevational view, partly in section, and a cross sectional view of the transporter and of the receiver, respectively.

In view of the above statements a brief description will suffice for explaining the construction and the modus operandi of the illustrated machine.

The stationary frame 1 serves to support the hollow casting 2, the curved top of which forms the rolling table. Said top is provided with a cross groove 3 for receiving the tobacco, and part of the top adjacent to this groove is provided with perforations 4. Stretched over the rolling table is a leather belt 5 passed over rollers 6, 7 at the top end of an arm 8, which is pivoted to the frame 1 as at 9. The right hand end of the belt 5 is secured to the hollow casting 2 as at 10, the left hand end thereof being connected through a coiled spring 5^a to the frame 1 so that the belt is always stretched. A stamper 11 secured to the end of an arm 12 serves for pressing the tobacco into the groove 3.

The stationary receiver is designated by 13, the transporter by 14, and these members and also the hollow casting 2 are provided with means whereby they may be connected to a vacuum space.

The wrapper for a cigarillo to be formed on the rolling table is placed on the cover of the receiver 13 whence it is conveyed by the transporter 14 to the perforated portion of the rolling table. The transporter 14, which is provided with a nozzle 16 for the connection of a flexible vacuum pipe, is car-

ried by a frame 15 through links 17, 18 of equal lengths and pivoted to the transporter 14 and to the frame 15 in such a manner as to always remain parallel the one with the other. To the link 18 is secured an arm 19 carrying an anti-friction roller 20 guided by a suitably curved slot 21 in frame 1. By these means the transporter 14 may be moved into its extreme left hand and right hand positions to coact with the rolling table 2 and with the receiver 13, respectively.

The frame 15 carries a brush 22 adapted during the movement of said frame 15 to the right to come into contact with a cylinder 23 revolving in a container 23^a partly filled with glue, whereby the brush takes up some of the glue to spread it out on the right hand side edge portion of the wrapper supported by the receiver 13.

A roller 24 mounted on the frame 15 is adapted for coacting with a knife to be described in further detail hereinafter.

The frame 15 is supported at its left hand end, as at 25, by the arm 8, and at its right hand side, as at 26, by an arm 27. Arm 8 is pivoted to one end of a rod 28 having its other end hinged to a rod 29 pivotally mounted on the frame 1. Said rod 29 carries an antifriction roller 30 held in contact with a cam 31 by means of a spring 29^a.

The arm 27 is pivoted to a bell crank lever 32, 33 pivoted to the frame 1 as at 32^a and having an antifriction roller 34 cooperating with a cam 35.

The arm 12 is secured to an arm 37 pivoted to the frame 1 as at 37^a and carrying an antifriction roller 38 contacting with the periphery of a cam 39.

Cams 31, 35 and 39 are keyed on a common shaft 40.

The transporter 14, see Fig. 2, is in the form of a casing having a perforated bottom 41 and lugs 42, 43 for receiving the pins with which it is pivoted to links 17, 18. Mounted on a stud 44 is the edge protector 45 having its under face flush with the bottom face of the transporter when assuming the position shown. Said edge protector 45 is provided with a projection 46 and loaded by a coiled spring 47 which is secured to a fixed pin 47^a of the transporter and to a pin 47^b of the edge protector so as to hold the latter in the position shown, or in a position wherein it is turned away from the casing, dependent upon whether the pin 47^b is at the left hand side or at the right hand side of the line passing through pivot 44 and pin 47^a.

The receiver 13, see Fig. 3, is in the form of a casing having a perforated cover 48, a knife 49 being screwed to the right hand side wall and adapted for coaction with the roller 24 (Fig. 1). The cover 48 has an enlarged right hand end portion having an outwardly sloping face 50, the outer edge

of which is normally at some vertical distance above the cutting edge of knife 49. Along its left hand edge said cover is hinged to the casing by means of a pin 51. A 5 spring 48^a always tends to hold the cover 48 in contact with a fixed stop member 48^b in the position shown. However, when an abutment 52 of frame 15 (Fig. 1) engages a roller 53 mounted on a laterally projecting 10 part of cover 48, the latter is depressed against the action of spring 48^a.

The receiver is further provided with a finger 54 adapted to coact with the projection 46, which further cooperates with a 15 finger 36 on arm 12.

The modus operandi of the described arrangement is as follows:

A wrapper is placed on the receiver cover 48 and cut at its right hand side edge by the 20 roller 24 moving over the cutting edge of knife 49, whereupon the brush 22 gums the right hand side edge portion of the wrapper supported on the sloping face 50. Finally the wrapper is picked up by the transporter 25 14 and conveyed to the rolling table. Any one skilled in the art will understand during which periods vacuum is applied to the receiver 13, the transporter 14 and the hollow casing 2 in the course of these operations.

30 When the roller 24 moves over receiver 13, the cover 48 is depressed by the coaction of the abutment 52 and roller 53 so that the roller 24 cannot come into contact with gum that may be on the sloping face 50. When 35 the abutment 52 releases roller 53, i. e. before the brush 22 has reached the sloping face, the cover 48 resumes its normal position under the action of spring 48^a, so that said brush is adapted to spread its gum on 40 that portion of the wrapper which is supported by the sloping face 50.

After the brush has done its duty, the transporter 14 is placed in proper position on the cover 48 whereby the projection 46 45 engages the finger 54 and the edge protector 45 is returned into the position shown in full lines in Fig. 2, so that the bottom face of said protector may engage the gummed edge portion of the wrapper. At this moment 50 vacuum is applied in the transporter casing and atmospheric pressure conditions restored in the receiver casing whereby the wrapper is forced against the bottom face of the transporter.

55 As soon as the wrapper carrying transporter has assumed its proper position on the rolling table, the stamper 11 moves down, thereby forcing the tobacco, which has previously been placed on the belt 5 vertically above the groove 3, into said groove together with part of the belt. At the same time the finger 36 engages the projection 46 so as to impart to the edge protector 45 an angular motion whereby the latter is forced 60 off the wrapper. Subsequently atmospheric

pressure is restored in the transporter casing and vacuum applied to the casting 2, so that the gummed wrapper adheres to the rolling table.

Finally the frame 15 with the parts associated therewith is again moved to the right for preparing and picking up a next wrapper, and the cigarillo is rolled on the rolling table in the ordinary manner.

Having now particularly described and ascertained the nature of my present invention and the manner in which the same is to be performed, I declare that what I claim is:

1. In a machine for manufacturing cigars and the like, a perforated rolling table having a groove, a perforated flexible band stretched over said table, means for actuating said band, a stamper for forcing tobacco into said groove, a frame carrying gumming means and a pneumatic transporter, means for supporting and actuating said frame and a stationary pneumatic receiver adapted to cooperate with said transporter and gumming means.

2. In a machine for manufacturing cigars and the like, a perforated rolling table having a groove, a perforated flexible band stretched over said table, means for actuating said band, a stamper for forcing tobacco into said groove, a frame carrying gumming and cutting means, means for supporting and actuating said frame and a stationary pneumatic receiver adapted to cooperate with said transporter and gumming and cutting means.

3. In a machine for manufacturing cigars and the like, a perforated rolling table having a groove, a perforated flexible band stretched over said table, means for actuating said band, a stamper for forcing tobacco into said groove, a frame carrying gumming means and a cutting roller and a pneumatic transporter, means for supporting and actuating said frame, and a stationary pneumatic receiver adapted to cooperate with said transporter and gumming means and cutting roller.

4. In a machine for manufacturing cigars and the like, a perforated rolling table having a groove, a perforated flexible band stretched over said table, means for actuating said band, a stamper for forcing tobacco into said groove, a frame carrying a pneumatic transporter, said frame being transported at one side by the means for actuating said band, means for supporting and actuating said frame and a stationary pneumatic receiver adapted to cooperate with said transporter and gumming means.

5. In a machine for manufacturing cigars and the like, a perforated rolling table hav-

ing a groove, a perforated flexible band stretched over said table, means for actuating said band, a stamper for forcing tobacco into said groove, a frame carrying a 5 pneumatic transporter, said frame being transported at one side by the means for actuating said band, a driven member for supporting the other side of said frame, means for supporting and actuating said 10 frame and a stationary pneumatic receiver adapted to cooperate with said transporter and gumming means.

6. A machine as claimed in claim 1 including parallel links pivotally connecting 15 said transporter to said frame, one of said links being provided with a guide member, and means whereby, when the frame is moved in opposite directions, the pneumatic transporter is moved relatively to the frame 20 in the same directions.

7. A machine as claimed in claim 1 including parallel links pivotally connecting said transporter to said frame, one of said links being provided with a guide member, 25 and a stationary piece provided with a guide slot for the guide member, whereby, when the frame is moved in opposite directions, the pneumatic transporter is moved relatively to the frame in the same directions.

8. A machine as claimed in claim 3 in which the pneumatic receiver includes a cover hinged at the end opposite said knife, the upper surface of said cover adjacent 35 said knife being inclined outwardly and upwardly, means for yieldingly maintaining the inclined surface of the cover above the cutting edge of said knife, and means for depressing said cover during the coaction of 40 the cutting roller with the knife.

9. A machine as claimed in claim 1 in which the pneumatic transporter is provided with a hinged member arranged in a position corresponding with that of the

gumming place of the pneumatic receiver 45 and adapted to be moved with its bottom face flush with the bottom face of the transporter on its way to the rolling table, and means for swinging said member away from the transporter when the transporter 50 arrives above the rolling table.

10. A machine as claimed in claim 1 in which the pneumatic transporter is provided with a hinged member arranged in a position corresponding with that of the 55 gumming place of the pneumatic receiver and adapted to be moved with its bottom face flush with the bottom face of the transporter when the latter is on the way to the rolling table, said member being provided 60 with an arm, a projection on the stamper adapted to actuate said arm, and another projection on the receiver adapted to actuate said arm.

11. A machine of the character described 65 including a perforated rolling table provided with a groove, a band stretched over said table, spaced rollers over which said band passes, a lever carrying said rollers, cam mechanism for actuating said lever, a 70 stamper cooperating with said groove and actuated by said cam mechanism, a pneumatic receiver provided with a movable cover and having a cutting knife arranged 75 near one end of the same, a movable frame actuated by said cam mechanism, a pneumatic transporter supported by said frame and adapted to be moved by the latter from the receiver to the rolling table and vice 80 versa, gumming elements arranged in the path of movement of said frame, a gumming brush carried by the frame and cooperating with the gumming elements, and a roller carried by the frame and cooperating 85 with said cutting knife.

In testimony whereof I affix my signature.

ADOLF BARGEBOER.
